(57) **CLAIM**

The ornamental design for a front cowl for motorcycle, as shown and described.

DESCRIPTION

FIG. 1 is a perspective view from the right side of a front cowl for motorcycle.

FIG. 2 is a perspective view of the opposite side shown in FIG. 1.

FIG. 3 is a perspective view from the left side thereof.

FIG. 4 is a perspective view of the opposite side shown in FIG. 3.

FIG. 5 is a front elevation view thereof.

FIG. 6 is a rear elevation view thereof.

FIG. 7 is a right side elevation view thereof.

FIG. 8 is a left side elevation view thereof.

FIG. 9 is a top plan view thereof.

FIG. 10 is a bottom plan view thereof; and,

FIG. 11 is a view showing the claimed front cowl for motorcycle shown on a reduced scale and in position of use on a motorcycle, which is shown in broken lines and forms no part of the claimed design.

The portions shown in broken lines form no part of the claimed design.
